CLAIM

The ornamental design for a synthetic drumhead, as shown and described.

DESCRIPTION

FIG. 1 is a perspective view of a synthetic drumhead showing our new design;

FIG. 2 is a perspective view thereof, having a radial section cutout therefrom;

FIG. 3 is a top plan view thereof;

FIG. 4 is a side elevational view thereof;

FIG. 5 is a cross-sectional view thereof, taken along line 5—5 of FIG. 3; and,

FIG. 6 is a bottom plan view thereof.
